UNITED STATES PATENT OFFICE.

EMIL TYDEN, OF EVANSTON, ILLINOIS.

MOUTHPIECE-SEAL LOCK FOR CANS AND THE LIKE.

1,145,099.

Specification of Letters Patent.

Patented July 6, 1915.

Application filed January 5, 1914. Serial No. 810,402.

To all whom it may concern:

Be it known that I, EMIL TYDEN, a citizen of the United States, residing at Evanston, in the county of Cook and State of Illinois, have invented new and useful Improvements in Mouthpiece-Seal Locks for Cans and the like, of which the following is a specification, reference being had to the accompanying drawings, forming a part thereof.

10 The purpose of this invention is to provide an improved device for closing a mouth-piece such as that of a can, tank or discharge pipe from any receptacle adapted to prevent the closure from being loosened in the least 15 while remaining sealed.

It consists in the elements and features of construction shown and described, as indicated in the claims.

In the drawings:—Figure 1 is a top plan view of a portion of a can having its mouth provided with a closure embodying this invention. Fig. 2 is a section at the line, 2—2, on Fig. 1. Fig. 3 is a section at the line, 2—3, on Fig. 2. Fig. 4 is a view similar to Fig. 1 of a modified form. Fig. 5 is a section at the line, 5—5, on Fig. 4. Fig. 6 is a section on an enlarged scale at the line, 6—6, on Fig. 5. Fig. 7 is a view similar to Fig. 6, showing the seal-receiving parts at unlocked 30 position,—that is, without the seal.

In transporting liquids in cans or other receptacles from which they are to be poured, the filling mouth is also customarily the discharge mouth and is most conveniently provided in a mouth-piece adapted to be closed by a screw-cap or plug. Especially in the case of volatile liquids such as gasoline, large waste is liable to occur from even slight loosening of the screw-cap or plug, 40 and it is possible for large stealings to be made in the course of transportation by merely loosening the screw-cap or plug and inverting the receptacle into a vessel which may receive the leakage. For these and other reasons it is very desirable to provide 45 means for sealing such receptacle closures so that they cannot be loosened without disclosing the fact by the mutilation or removal of the sealing devices; and, this is accomplished by the present invention.

In the drawings, A represents a portion of the can body having a mouth-piece fitting, B, which is in common form, in that it is an exteriorly-threaded fitting adapted to be 55 closed by an interiorly-threaded cap (a re-version of these details is entirely consistent

with the invention). The mouth-piece fitting, B, has an annular flange, B¹, about the mouth, exteriorly threaded, as stated, to receive the closure, C, which is a cap interiorly threaded for screwing onto the exteriorly-threaded flange of a mouth-piece.

D is an outer cap or hood which incloses the closure cap, C, the latter being rotatably mounted in the cap, D, such mounting being most conveniently effected by providing the closure, C, with an axially-extended stem, C¹, which is inserted through a central aperture in the top of the cap D, and has its end riveted down, over a retaining collar, C², which collar is accommodated in a counter-bore, D², about the central aperture, D¹, of the cap, D, the riveted end of the stem, C¹, and the retaining collar, C², being completely covered and rendered inaccessible by a plate or disk, F, let into the counterbore, and accommodated within the depth thereof, said counter-bore being additionally counter-bored to form a shoulder, d¹, on which the plate, F, seats, the margin of the counter-bore being riveted down over the periphery of the plate and retaining it securely enough to prevent any access, except by such violent means as will be obvious and give evidence of the tampering of the device. The closure cap, C, is thus swiveled in the outer cap or hood, D, with perfect freedom to turn about the axis; but the amount of turning which is possible is limited by a stop, c, projecting up from the top of the cap, C, and a co-operating stop, d, projecting down from the inner surface of the top of the cap, D, said upper surface of the cap, C, and inner surface of the cap, D, being spaced apart to accommodate the stops, c and d, by the expedient of forming a shoulder, c¹, on the stem, C¹, of the cap, C.

The two caps being connected as described, it will be seen that the outer cap, D, may be rotated relatively to the closure cap, C, one full turn less the angle occupied by the two stops, c and d; and it will be seen that upon applying the device comprising the closure, C, and the cap, D, to the mouth piece, and rotating the cap, D, to the right (assuming the thread of the mouth-piece and closure to be a right-handed thread). The engagement of the stop, d, with the stop, c, will cause the closure cap, C, to be rotated, screwing it down upon the mouth-piece until it is tight, and that upon then reversing the rotation of the cap, D, it may

be given nearly a full turn without causing the stop, *c*, to encounter the stop, *d*, and therefore without any possibility of unscrewing the closure cap from the mouth-piece.

The mouth-piece is provided with a lug, *B*³, which, as shown, projects up from the margin of its base flange, *B*¹, parallel to the axis, and the cap, *D*, has a flange, *D*², whose diameter is sufficient to cause it to extend to the foot of the lug, *B*³, and at the margin of this flange there is provided an up-standing lug, *D*³, corresponding to the lug, *B*³, and adapted to be opposite the latter when the cap has been backed through a relatively small angle from the point at which it stands upon completing the driving home of the closure cap, *C*. The angle mentioned provides for the unavoidable variation in the position at which the thread will become tight on different fittings when made as nearly uniform as possible, and such further variation as will arise in the use of the device after repeated tightenings and loosenings, the necessity being that it shall in all cases be possible to bring the herein-after mentioned seal slots in the two lugs, *D*³ and *B*³, into registration with each other when the closure cap has been screwed tight, and without using up any more than a small portion of the range of reverse movement of the cap, *D*. The two lugs, *B*³ and *D*³, are provided with seal slots, *b*³ and *d*³, which are registered when the two lugs are opposite each other so as to receive through them both the securing member of any suitable sealing device which is represented in the drawings by a seal having a metal strip, *G*, as a securing member. Preferably the slots, *b*³ and *d*³, have their length in a plane transverse to the axis of the device, so that the sealing strip is presented edgewise to any attempted movement of the cap, *D*, for unscrewing, thus defeating any possibility of drawing the strip between the lugs, *B*³ and *D*³, and insuring that the strip will be sheared in two if the cap, *D*, is forced out of sealed position.

It will be seen that the invention is not limited in its essential character to what might be strictly described as a threaded closure fitting, but, on the contrary, any closure fitting adapted to be secured by rotation, may be equipped with this invention. Also, it will be observed that it is not limited to the particular kind of seal shown, but, on the contrary, any seal having its securing member or device adapted to defeat relative rotation of the cap and mouth-piece, can be employed with suitable modification of the members provided for its engagement with the cap and the mouth-piece.

For convenience of manipulation, it is preferred to form the upper end of the cap, *D*, with bosses, *d*⁴, *d*⁵, which may be engaged

by any straight rod or bar for unscrewing the cap.

In Figs. 4 to 7, there is shown a modification of the invention. In this form, instead of providing the closure and the outer cap with the engaging lugs, *c* and *d*, respectively, the outer cap, *D*, has mounted in it a plunger bolt, *H*, and the closure cap, *C*, has in its head a socket, *c*⁵, to receive the plunger bolt. This plunger bolt serves as a means of engaging the outer cap, *D*, with the closure cap, *C*. For housing the plunger, a relatively long cylindrical boss, *D*⁶, projects up from the cap, *D*, and has a slot, *d*⁶, which is engaged by a spline, *h*, on the plunger, *H*, permitting and guiding the vertical reciprocation of the plunger. This slot extends to the top of the boss so that the spline runs out of it at the upper limit of its movement;—that is, when the plunger bolt is drawn out of engagement with the closure cap, *C*, and when thus withdrawn, the plunger, *H*, which is prevented from further withdrawal by its enlarged head, *H*¹, encountering an interior shoulder, *d*⁸, in the boss, *D*⁶, can be rotated in the boss, causing the spline to be stopped upon the top of the boss, and prevent the depression of the plunger until it is turned around again into line with the slot.

At a position about 90 degrees around from the spline, *h*, the plunger, *H*, has a slot, *h*⁸, cut diametrically through it, which registers with the slot, *d*⁶, when the plunger is withdrawn, so that the spline, *h*, rides upon the top of the boss and has been turned 90 degrees around from the slot, *d*⁶. At this position it will be seen that the securing member, *G*, of the seal can be inserted through the slots in the boss and plunger, and when so inserted, will prevent the plunger being rotated and so will prevent it being depressed into closure-engaging position. When the device is thus sealed, it will be seen that the cap, *D*, is powerless to rotate the closure cap, *C*. It will be understood that this modification can be operated in substantially the same manner as that of the form first described. That is to say, when unsealed, the plunger, *H*, being turned so as to register the spline with the slot, *d*⁶, and pressed down while the cap, *D*, is rotated, will presently come into engagement with the socket, *c*⁵, thus engaging the cap, *D*, with the closure cap, *C*, whereupon the closure cap can be screwed home. This having been done, the operator retracting the plunger and returning it to seal-receiving position, will insert and secure the seal, preventing the possibility of engagement of the closure cap by the outer cap, *D*, without removal of the seal.

I claim:

1. In combination with a mouth-piece, a closure for the same adapted to be engaged

- therewith for rotation about an axis; a cap inclosing said closure, having the latter rotatably mounted in it; devices for engaging the cap with the closure for rotation of the latter about the former, the mouth-piece and the cap having members adapted to be seal-connected against relative rotation at a disengaged position of the cap and closure. 5
2. In combination with a screw-threaded mouth-piece and a screw-threaded closure for the same, a cap inclosing a closure, having the latter rotatably mounted in it; devices for engaging the cap with the closure for rotation of the latter by the former, the mouth-piece and the cap having members adapted to be seal-connected against relative rotation at a disengaged position of the cap and closure. 10
3. In combination with a mouth-piece, a closure for the same adapted to be engaged therewith for rotation about an axis; a cap inclosing a closure, having the latter rotatably mounted in it; coöperating stops on the cap and closure which are inclosed within the cap, adapted to be engaged and to permit a limited rotation of the cap with respect to the closure in coming into engagement, the mouth-piece and the cap having members adapted to be seal-connected against relative rotation at a disengaged position of said stops. 15
4. In combination with a mouth-piece, a closure for the same adapted to be engaged therewith for rotation about an axis; a cap inclosing the closure having the latter ro- 20
5. In combination with a mouth-piece, the cap having members adapted to be seal-connected against relative rotation at an unengaged position of said engaging devices, one of said seal-connected elements having two such members at opposite sides of the axis, whereby choice of two positions for effecting the seal connection is afforded. 40
6. In combination with a mouth-piece, a closure for the same adapted to be disengaged therefrom by rotation about an axis; a cap inclosing a closure, said two members being swiveled to each other at their axis; devices for engaging the cap with the closure for rotation of the latter by the former, the mouth-piece and cap having members adapted to be seal-connected at an unengaged position of said devices. 45
7. In combination with a mouth-piece, a closure for the same adapted to be engaged therewith for rotation about an axis; a cap inclosing the closure, the latter having an axially-extended stem by means of which it is swiveled to the cap, the cap having a permanently secured plate covering the end of the stem from exterior access. 50
- In testimony whereof, I have hereunto set my hand at Chicago, Illinois, this 31st day of December, 1913. 55

EMIL TYDEN.
